UNITED STATES PATENT OFFICE.

EDWARD W. N. BOOSEY, OF DETROIT, MICHIGAN.

WATER-CLOSET BEND.

Application filed June 29, 1925. Serial No. 40,416.

This invention relates to plumbing fixtures particularly water closet bends which make the connection of the closet with the soil pipe and which carries the soil from the 5 closet to the stack and so constructed as to provide for the discharge of the waste from the bath tub, lavatory or other fixtures into the bend. The object of the invention is to provide a bend of wrought iron construction 10 for threaded engagement with the various pipe connections which are usually of cast iron.

In the present type of building construction the use of the old type of cast iron 15 closet bends adapted to be caulked to the piping are inadequate for the purpose due to the fact of their being readily broken but which, with a wrought iron connection, is largely eliminated. A particular feature of 20 the invention is in the provision of a closet bend of wrought iron construction that is simple in form adapted for threaded connection with the pipe or fixtures to be connected therewith and further so arranged that it 25 provides for the carrying of waste from lavatories, bath tubs, etc., to the soil pipe stack through the bend and being connected with the bend which is so constructed at the point of connection that a possibility of the siphoning 30 of the various lines there connected is eliminated. I am aware of cast iron bends provided with a hub for connection of a waste piping bend above the level of the water that may flow through the bend thus 35 opening the pocket to the stack above the level of the water in the bend and thus venting of what may be termed a "pocket" with which the waste line is connected. In this 40 present construction I have provided a pocket of somewhat different character which is not vented through the bend but is directly vented by a vent line to atmosphere or to the stack, the construction providing a pocket above the possible level of the flow of 45 the fluid through the bend, which pocket is not vented to the discharge stack through the bend. These objects and the several 50 novel features of the invention are herein after more fully described and claimed, and the preferred form of construction of a closet bend embodying my invention is shown in the accompanying drawings in which—

Fig. 1 is a side view of my improved bend.

Fig. 2 is an end view thereof.

Fig. 3 is a longitudinal section showing

clearly the improved arrangement of the pocket for the connection of waste piping or the likee with the bend.

As previously stated, the bend here shown and described is formed of wrought iron for 60 screw-threaded connection with the piping or fixtures to be connected therewith. This, as is shown clearly in the drawing, is of the usual general form of the bend having the threaded end 1 to receive the fitting with 65 which the closet may be connected to the bend (not here shown) and at the opposite end is provided with the threaded hub 2 which is connected with the stack by a short 70 piping. On the surface of the bend I provided what I have termed a pocket 3 which is above the general level of flow of fluid through the bend as will be understood from Fig. 3. This pocket, as stated, is formed on the upper side of the bend and on the interior of the bend a depending lip 4 is provided at the forward end of the pocket which in reality determines the effect of the bore of the bend for the passage of the fluid. At the rear end the pocket also has a second 75 depending flange 5 which terminates above the flange 4 and provides a venting of the pocket to the discharge piping with which the bend is connected through the bend itself. The purpose of venting the pocket to 80 atmosphere as has been previously stated, is to prevent a siphonage of the conduits connected with the pocket and the structures herein used for the purpose, although the connection of the piping to the bend may be 85 above the general level of flow of liquid therein, yet upon discharge of the closet this area at the rear of the bend does not always provide a proper vent space particularly 90 where several such closet bends are connected with a single stack and flushed simultaneously. This pocket is provided with 95 threaded hubs on opposite sides indicated at 6 and 7, for the connection of waste piping 100 from lavatories, sinks etc., and is provided on the upper surface with a threaded hub 8 to which the vent pipe may be connected leading to atmosphere and this venting of the pocket is more effective than with the methods heretofore used as there is no possibility of closing the pocket to atmosphere and thereby siphoning the waste connections to the pocket as has been possible with such structures in which the pocket was vented 105 through the bend to the stack. By this gen- 110

eral arrangement described a movable fitting is provided for connecting the closet, water conduits, and vent at one point in the drainage system of the modern type in which the 5 fittings and pipe connections are screw-threaded.

From the foregoing description it becomes evident that the device is very simple and efficient in operation, will not easily get out 10 of order, is of comparatively low manufacturing cost, and provides a device which accomplishes the objects described.

Having thus fully described my invention, its utility and mode of operation, what I 15 claim and desire to secure by Letters Patent of the United States is—

1. A water closet bend having threaded inlet and outlet ends, said bend being constructed with a pocket in the upper surface 20 between the said ends, the wall defining the pocket at the forward end extending below the wall defining the pocket at the rear end, the said pocket having hubs for the connection of waste piping, and a vent connection 25 in the upper side thereof.

2. In a water closet bend having an inlet end for the connection with a closet fixture and an outlet end for connection with a waste conduit and a pocket in the upper sur-

face thereof above the outlet end of the bend, 30 the forward wall of the pocket extending nearer the longitudinal axis of the bend than the rear wall of the pocket, an inlet in communication with the said pocket and a connection for a vent in the upper part of 35 the pocket.

3. A water closet bend having an inlet end, the axis of which is in a vertical plane and adapted for connection with a closet bend, and an outlet end, the axis of which 40 is in a horizontal plane adapted for connection of a conduit therewithin, a pocket formed in the upper surface of the bend above the bore and extending from the side of the inlet end to adjacent the outlet end, 45 the rear wall of the pocket extending into the bore and the forward wall of the pocket extending to a plane below the plane at which the rear wall terminates and restricting the flow through the inlet to a volume 50 less than that permitted by the terminal portion of the rear wall, said pocket having hubs in the side thereof for a waste pipe connection and an opening for a vent connection in the upper surface. 55

In testimony whereof, I sign this specification.

EDWARD W. N. BOOSEY.
